UNITED STATES PATENT OFFICE.

FRIDOLIN SCHIMMEL, OF FARIBAULT, MINNESOTA.

BOOK-RACK.

1,336,981.

Specification of Letters Patent. Patented Apr. 13, 1920.

Application filed May 19, 1919. Serial No. 298,073.

To all whom it may concern:

Be it known that I, FRIDOLIN SCHIMMEL, a citizen of the United States, residing at Faribault, in the county of Rice and State 5 of Minnesota, have invented certain new and useful Improvements in Book-Racks; and I do hereby declare the following to be a full, clear, and exact description of the invention, such as will enable others skilled 10 in the art to which it appertains to make and use the same.

My invention has for its object to provide a simple and efficient book rack of a character adapted to be set on a table or on 15 a shelf to hold a comparatively small number of books; and to such ends, generally stated, the invention consists of the novel devices and combinations of devices hereinafter and described and defined in the 20 claims.

The invention is illustrated in the accompanying drawings wherein like characters indicate like parts throughout the several views. Referring to the drawings:—

25 Figure 1 is a side elevation of the improved rack showing several books held thereby, some parts of the base of the rack being broken away;

Fig. 2 is a plan view of the rack;

30 Fig. 3 is an enlarged view chiefly in section on the line 3—3 of Fig. 2, but with some parts shown in full, and some parts broken away;

Fig. 4 is a fragmentary vertical section 35 on the line 4—4 of Fig. 3; and

Fig. 5 is a section on the line 5—5 of Fig. 2, some parts being removed.

The base of the rack is formed from a flat board 6, preferably of more or less 40 ornamental design. This board, in its underside, is formed with longitudinally extended centrally located grooves 7 that have relatively narrow slots 8 cut completely through the board or base 6.

45 Mounted to slide on top of the base board 6 are two book clamping heads made up, preferably of parallel upright wooden plates 9 and brackets 10 rigidly secured thereto. The under edges of the plates 9 and brackets 10 are preferably faced with felt or other pliable strips 11 that directly engage the upper surface of the base board 6 and prevent the same from being marred or scratched.

50 Each clamping head is provided with a

substantially flat spring metal clamping strip 12 attached thereto by screws 13 and 14. The screws 13 and 14 are screwed, respectively, into the plates 9 and their brackets 10 and extend through and slide in the 60 respective slots 8 with the clamping strips 12 working in the corresponding grooves 7. The clamping strips 12 are slightly narrower than the grooves 7, but considerably wider than the slots 8, so that they will 65 clamp against the undersurfaces of the flanges formed in the base board 6 by the grooves 7 and slots 8. Screws 13 are adjusted so that there is but slight clearance between the inner ends of the clamping 70 strips 12 and the said flanges, but the screws 14 are adjusted so that there is very considerable clearance between the outer ends of said clamping strips and the said flanges. Those portions of the spring clamping strips 75 12 that are closely adjacent to screws 13, yieldingly press against the flanges noted on the base 6 and tend to hold the head plates 9 in vertical positions, or at right angles to the base 6. These clamping strips 80 12 will yield readily to permit the heads to be moved, the one toward the other and against the books 9, but pressure applied to the heads by the books clamped between the heads, will be in an outward direction, 85 and, as the inner edge of the clamping strips 12 are unyieldingly held by the screws 13, and as the brackets 10 prevent the head plates 9 from being rocked outward, there will be a clamping or biting action sufficient to prevent accidental outward 90 sliding movement of the clamping heads. To release the clamping heads from the books and to slide the same outward, it is necessary to first press the upper edges of 95 the heads against the books more tightly, so as to tilt the heads and slightly raise the brackets 10, whereupon the said clamping heads may be slid outward or away from the books.

100 This improved book rack has, in practice, been found highly efficient for the purposes had in view, and moreover, may be manufactured at small cost. Obviously, it may be made in any desired ornamental design. 105

By reference, particularly to Fig. 3, it will be noted, that the clamping strips and the heads of the screws are always within the grooves 7 and above the undersurface of the base board 6, so that they cannot mar 110

or scratch a table or shelf on which the rack is set. Also, it is evident that as the two clamping heads are adjustable, it is always possible to clamp a set of books, or 5 several books between the heads with the books at the central portion of the rack, and this, as is evident, gives the best appearance.

What I claim is:

- 10 1. A book rack comprising a base board formed in its under side with a groove and with a relatively narrow slot opening from said groove to the top of the board, clamping heads applied on said board, at least 15 one thereof being adjustable toward and from the other, curved spring metal clamping strips working in said groove and being wider than said slot, and screws connecting the ends of said clamping strips to said 20 clamping head, through said slot, the inner screw being adjusted to closely clamp the inner end of said clamping strip against the flanges formed by said groove and slot, and the outer screw being adjusted to afford

large clearance between the outer ends of 25 said clamping strip and said flanges.

2. A book rack comprising a base board formed with alined longitudinal grooves, and relatively narrow slots opening from 30 said grooves through the top of said board, a pair of clamping heads slidably mounted on said board, curved spring clamping strips working in said grooves and being wider than said slots, and screws 35 connecting the ends of said clamping strips through said slots, and to the respective clamping heads, the inner screws being adjusted to cause said clamping strips to engage the flanges of said base board adjacent to the inner screws leaving large 40 clearance between said flanges and the outer ends of said clamping strips.

In testimony whereof I affix my signature in presence of two witnesses.

FRIDOLIN SCHIMMEL.
